IMOGEN N. THOMAS, OF TROY, NEW YORK.

CHARGING-FITTING FOR BEVERAGE-CARBONATORS.

1,269,130.

Specification of Letters Patent. Patented June 11, 1918.

Application filed November 28, 1916. Serial No. 133,843.

To all whom it may concern:

Be it known that I, IMOGEN N. THOMAS, a citizen of the United States, residing at Troy, in the county of Rensselaer and State of New York, have invented a new and useful Improvement in Charging-Fittings for Beverage-Carbonators, of which the following is a specification.

This invention relates to a fitting which is designed to be applied to a fountain or similar beverage container and be connected with piping from a source of carbon dioxid under pressure; with piping from a supply of pure or mineral water which is to be charged with the gas and retained in the fountain under pressure until dispensed or drawn for further use; and with piping to the draft outlet or draw off.

The object of the invention is to provide a simple, cheap and compact fitting that may be readily applied to or removed from a fountain or similar container for charged liquid, which is so constructed that the several necessary pipe connections and required safety and escape valves can be easily and quickly attached in such manner that the joints will be tight, and the liquid and gas commingled very efficiently and economically.

Of the accompanying drawings Figure 1 is a central vertical section of the fitting showing it attached to the head of a fountain. Fig. 2 shows a plan of the fitting. Fig. 3 shows a side view of the fitting, without the water sprayer and the outflow tube. Fig. 4 is a horizontal section taken on the plane indicated by the dotted line 4—4 on Fig. 1. Fig. 5 is a horizontal section of the fitting on the plane denoted by the dotted line 5—5 on Fig. 1.

The fitting illustrated has a cylindrical body 1. Extending downward from the lower side of the body is a stem 2 that is threaded so that it may be readily screwed into the mouth in the top 3 of a fountain, and extending upward from the upper side of the body is a hub 4 that is of angular outline for the convenient application of the wrench which may be used to screw the stem into or unscrew it from the mouth of the fountain.

In the center of the body of the fitting and opening downward through the stem is a chamber 5, and extending from the periphery radially inward to this chamber is a passage 6. The walls of the outer end of

this passage are threaded for the convenient connection of the piping from the source of water supply.

Passing vertically through the middle of 60 the chamber 5 and opening through the upper end wall is a tube 7. This tube is designed to extend downward, when the fitting is in place for use, to nearly the bottom of the fountain, and at its upper end it has a 65 flange 8 that is secured in the bottom of the opening 9 that is threaded for the convenient connection of the end of the piping which leads to the draft faucet or draw off. A perforated conical shell or sprayer 10 is 70 secured to the bottom of the stem over the lower end of the chamber 5 and about the outflow tube 7.

Opening part way into the body from one side is a passage 11. The walls of the outer 75 end of this passage are threaded for the connection of the piping from the supply of gas. From the inner end of this passage down through the body is a hole 12, and in line with this hole the threads on the exterior of the stem are cut away so as to form a groove 13 in the outer wall of the stem. Opening part way into the body from another side is a passage 14, the walls of which at the outer end are threaded for the connection of the stem of a safety valve that may be provided to relieve any excess pressure in the fountain. A hole 15 is made from the inner end of this passage down through the bottom of the body, and in line 80 with this hole the threads on the stem are cut away so as to form a groove 16. At another point a radial passage 17 may be made from the periphery part way into the body, and the outer end of this opening may be 90 threaded for the connection of the stem of a blow off cock. A hole 18 is made from the inner end of this passage down through the body, and the threads of the stem in line 95 with this hole are cut away to form a groove 100 19. A gasket or lead washer 20 is fitted upon the base of the stem to insure against leakage when the fitting is screwed into the mouth of a fountain.

When the fitting is screwed into the mouth 105 of the fountain ready for use the water supply pipe is connected with the passage 6 and at the desired time water is allowed to enter through this passage to the chamber 5 and flow down through the sprayer 10 and 110 out into the fountain. The gas supply pipe is connected with the passage 11 and

the gas when allowed to enter flows down into the fountain through the groove 13 cut across the threads of the stem. As the gas enters near the top of the fountain and the 5 water is thrown out and diffused by the sprayer adjacent to the point of entry of the gas, the water and gas commingle so that the water absorbs the gas very quickly and thoroughly. The outflow or draw off pipe 10 is designed to be connected with the passage 9 and when charged fluid is drawn out it flows up from the bottom of the fountain through the tube 7 to the passage 9. If a safety valve is connected with the passage 15 14 the gas pressure is exerted upward through the groove 16 cut across the threads of the stem so as to actuate the safety valve, and if a relief valve is connected with the passage 17, when it is opened the fluid that 20 it is desired to allow to flow out passes upward through the groove 19 cut across the threads of the stem.

This fitting is an integral casting and the 25 chamber and passages are easily formed, particularly the grooves that are cut across the threads of the stem, thus making it very cheap to manufacture. It can be readily attached to or removed from a fountain and can be easily and quickly connected with 30 the gas, water and draft piping and provided with safety and relief valves if desired. The connections can all be made so as to eliminate the possibility of leaking and the gas and liquid are commingled in a 35 very efficient manner.

The invention claimed is;

1. A charging fitting for a beverage carbonator consisting of a body with an integral threaded stem having a groove cut across the threads of the stem, said body 40 having a central downwardly opening chamber with a passage opening through one side of the body to the central chamber and a passage opening into the body from one side and communicating with the groove 45 across the threads of the stem, a sprayer secured to the stem over the lower end of the central chamber in the body, and a tube passing through said sprayer and the central chamber and opening at one end below 50 the sprayer and at the other end above the top of the chamber.

2. A charging fitting for a beverage carbonator consisting of body with an integral threaded stem having three grooves cut 55 across the threads of the stem, said body having a central downwardly opening chamber with a lateral passage through the side of the body to said chamber and three lateral passages opening through the side of 60 the body and communicating each with a groove across the threads of the stem, a sprayer secured to the stem over the lower end of the central chamber in the body, and a tube passing through said sprayer and the central chamber and opening at one end below 65 the sprayer and at the other end above the top of the chamber.

IMOGEN N. THOMAS.
